UNITED STATES PATENT OFFICE.

ROBERT HAYES, OF ALMA CENTER, WISCONSIN.

ARMORED MOTOR-CAR.

1,248,325.

Specification of Letters Patent. Patented Nov. 27, 1917.

Application filed August 7, 1917. Serial No. 184,899.

To all whom it may concern:

Be it known that I, ROBERT HAYES, a citizen of the United States, residing at Alma Center, in the county of Jackson and State 5 of Wisconsin, have invented a new and useful Armored Motor-Car; and I do hereby declare the following to be a full, clear, and exact description of the invention, such as will enable others skilled in the art to which 10 it appertains to make and use the same.

This invention relates to an improved armored motor car, and an object of the invention is to provide a device of this kind having mountings, whereby guns, preferably breech loading rapid-firing or machine 15 guns may be mounted thereon, one on each side, and one at each end.

A further object of the invention is to provide an armored car, having the armor 20 so constructed adjacent the front wheels thereof, whereby said wheels may easily and readily turn.

A further object of the invention is to provide an improved frame for an armored 25 motor car, whereby the motor and its gearing to the drive wheels may be conveniently supported.

A further object of the invention is to provide an improved frame for an armored 30 motor car having means to readily and conveniently support four or more gunners for the rapid firing guns.

A further object of the invention is to provide an inclosed armor provided with 35 improved means, whereby the armor may be adjusted vertically.

A further object of the invention is to provide openings in the armor for the barrels of the guns, and shields having sight 40 openings and carried by the barrels, for covering said gun openings.

In practical fields the details of construction may necessitate alterations falling within the scope of what is claimed.

45 The invention comprises further features and combination of parts as hereinafter set forth, shown in the drawings, and claimed.

In the drawings:—

Figure 1 is a view in side elevation of the 50 improved armored motor car constructed in accordance with the invention.

Fig. 2 is a plan view of the same.

Fig. 3 is a longitudinal sectional view on line 3—3 of Fig. 2.

55 Fig. 4 is a sectional view on line 4—4 of Fig. 3.

Fig. 5 is a cross sectional view on line 5—5 of Fig. 2.

Fig. 6 is a cross sectional view on line 6—6 of Fig. 2.

Referring more especially to the drawings 60 1 designates the rear axle provided with rear supporting traction wheels 2, and supported on the axle in any suitable manner as shown at 3 is a skeleton motor frame 4. This motor truck frame is elongated and rectangular, and is provided with a plurality of transverse platforms 5, 6, 7 and 8 and secured to the platform 5 in any suitable manner is the front axle 9. Connected to the 70 ends of the front axle 9 by the usual or conventional knuckle joints 10 are the front wheels 11. The knuckle joints, in fact the stub shafts of the knuckle joints are provided with the usual rearwardly extending 75 arms 12, which are connected by the connecting rod 13. The frame 4 immediately adjacent the platform 5 is provided with a transverse bar 13, the central portion of the forward edge of which has an inclined bearing 14, in which the steering column 15 is mounted, there being collars 16 secured at 80 17 on the column, to support the column in the position shown. The steering column 15 is designed to carry the usual steering shaft 18 85 having its upper end provided with a steering wheel 19, and its lower end provided with a collar 20 secured in place by the pin 21. An arm 22 projects from the collar 20, and pivoted to the end of this arm as at 23 90 is a link 24, which in turn is pivoted at 25 to the cross bar 13, which connects the arm 12. It is to be noted that by turning the steering wheel 19 in one direction or the other, the front wheels may be turned correspondingly for steering the armored motor car. The platform 6 has secured to it by bolts 26 a conventional form of internal combustion motor or engine 27, the engine shaft (not shown) of which is provided with 100 the usual fly wheels 28. Secured upon the rear end of the engine shaft (not shown) as by means of a pin 29 is a sleeve coupler 30, and secured to the forward end of the shaft 31, as by means of a pin 32 is a sleeve coupler 33. These sleeve couplers are universally connected as at 34. This universal connection comprises the interconnected diametrically opposite forks which are of conventional construction. A differential gear 105 35 casing (which is carried by the rear axle 1 and is designed to contain the differential

gear mechanism not shown) is provided with a bearing 35 for the rear end of the shaft 31, the rear extremity of which is designed to connect and coöperate with the differential 5 gear mechanism (not shown) of said differential gear casing 36. By means of the motor 27 and its shaft and the shaft 31, power is transmitted to the rear axle 1 of the armored motor car for driving the same. 10 Secured by bolts 37 on the transverse platforms 5, 7 and 8 are suitable supports or gun mountings 38, on which conventional form of breech loading, rapid firing or machine guns 39 are pivotally mounted as 15 shown at 40 and which may operate in any conventional manner. An improved armor hood 41 is provided and which arches over the frame and the wheels, and also over the rapid firing or machine guns. This hood or 20 armor curves forwardly from the sides and also rearwardly from the sides, and the forward and rear ends of the top of the armor or hood curve or slope downwardly. The forward and rear and the side walls adjacent said guns have openings 42, through which the gun barrels of the guns project, whereby they may be trained on the enemy. Secured to and carried by the outer end portions of the gun barrels in any suitable manner as shown at 43 are shields 44, which 25 cover the openings 42, in order to shield the gunners. However, the shields 44 have sight openings 45 whereby the sights of the gun barrels may be alined on the object 30 aimed at. The forward end of the frame 4 of the armored motor car has its side rails bent inwardly V-shaped, as shown at 46. The armor or hood adjacent the front wheels has its opposite sides convexed or bulged 35 outwardly substantially semi-spherical shape as shown at 47, thereby forming hollows 48, which in conjunction with the V-shaped contour of the side rails of the frame constitute means to permit the front wheels 40 to easily and readily turn, when operated by the steering mechanism. Riveted or otherwise secured as shown at 49 to the inner side faces adjacent the lower parts of the sides of the armor are brackets 50. Each 45 bracket 50 is provided with a U-shaped portion 51, which arches downwardly on the side rails of the frame 4 of the armored motor car. The inner part of each U-shaped portion has an elongated slot 52, to receive 50 the shank of the set bolt 53, which shank is threaded into the side rail of the frame 4. Threaded in the arch of each U-shaped por-

tion of each bracket is an elongated adjusting screw 54, the lower end of which bears at 55 on the side rail of the frame 4 of the armored motor car. It is to be noted that by adjusting the screws 54 in one direction or the other, the armor or hood may be raised or lowered, and by means of the set bolts 53 the armor or hood may be held in 60 different adjusted positions. The armor is provided with a hinged door 56 for closing the opening 57, which opening is designed for permitting the entrance of the operators or gunners, there being a latch 58 for said door. This armored motor car is designed for advance charges, or may be operated in 65 trenches.

The invention having been set forth what is claimed as new and useful is:—

1. In an armored motor car, a wheel supported frame, a hood armor U-shaped in cross section arching over the frame and having its end walls sloping downwardly, the lower portions of the inner faces of the side walls of said armor having brackets provided with U-shaped portions arching over the side rails of the frames, the inner part of each U-shaped portion having an elongated slot, an adjusting screw threaded in the arch of each U-shaped portion and bearing against the side rail of the frame for adjusting the armor vertically, and means passing through said elongated slot and threaded into the side rail of the frame for holding the bracket and the hood in different vertically adjustable positions.

2. In an armored motor car, a wheel supported frame, a hood armor U-shaped in cross section arching over the frame, the lower portions of the side walls of said armor having U-shaped members arching over the side rails of the frame, the inner part of each U-shaped member having a guiding connection with the side rail of the frame, and means passing through the arch of each U-shaped member and bearing against the side rail of the frame for adjusting the armor vertically, said guiding connections having means for holding the U-shaped members and the hood in different vertically adjustable positions.

In testimony whereof I have signed my name to this specification in the presence of two subscribing witnesses.

ROBERT HAYES.
